COMBINED PENCIL AND PEN POINT PROTECTOR AND CLIP

Harry Esterow, New York, N. Y.

Application April 19, 1949, Serial No. 2,139

Term of patent 14 years

(Cl. D74—2)

To all whom it may concern:

Be it known that I, Harry Esterow, a citizen of the United States, residing in the city, county, and State of New York, have invented a new, original, and ornamental Design for a Combined Pencil and Pen Point Protector and Clip, of which the following is a specification, reference being had to the accompanying drawing, forming part thereof, in which

Fig. 1 is a front elevational view of a combined pencil and pen point protector and clip, showing my new design;

Fig. 2 is a side view of the same, and

Fig. 3 is a rear view of the same.

I claim:

The ornamental design for a combined pencil

and pen point protector and clip, substantially as shown.

HARRY ESTEROW.
